UNITED STATES PATENT OFFICE.

GUSTAV B. KEIL, OF CHICAGO, ILLINOIS, ASSIGNOR TO FEDERAL SIGN SYSTEM (ELECTRIC), OF CHICAGO, ILLINOIS, A CORPORATION OF NEW YORK.

GEARING.

1,323,772.

Specification of Letters Patent.

Patented Dec. 2, 1919.

Application filed June 11, 1917. Serial No. 173,960.

To all whom it may concern:

Be it known that I, GUSTAV B. KEIL, a citizen of the United States, and a resident of Chicago, in the county of Cook and State 5 of Illinois, have invented certain new and useful Improvements in Gearing; and I do hereby declare that the following is a full, clear, and exact description thereof, reference being had to the accompanying drawings, and to the letters of reference marked thereon, which form a part of this specification.

This invention relates to improvements in gearing and consists of the matters herein- 15 after described and more particularly pointed out in the appended claims.

The improved gearing is herein illustrated as applied to a washing machine of the cylinder type, the present invention includ- 20 ing means for driving and controlling a wringer mounted on the washing machine and which may be swung in a horizontal plane into any position, desired by the operator without destroying the driving connection between said wringer and the other 25 parts of the gearing.

The many advantages of my invention will appear as I proceed with my specification.

30 In the drawings:

Figure 1 is a view representing a front end elevation of a washing machine of the cylinder type, to which a gearing embodying my invention is applied.

35 Fig. 2 is a fragmentary view representing a side elevation of the same, with the wringer swung into a position at a right angle to that shown in Fig. 1.

Fig. 3 is a detail, vertical sectional view 40 through the gearing, the plane of the section being indicated by the line 3—3 of Fig. 1.

Fig. 4 is a detail, horizontal sectional view 45 through the washing machine, the plane of the section being indicated by the line 4—4 of Fig. 2.

Referring now in detail to that embodiment of my invention illustrated in the drawings:—10 indicates a main support for the gearing which, as illustrated in this particular instance, is the tub of a washing machine of the drum or cylinder type. The tub is mounted at its corners upon upright legs, arranged in pairs, only the front pairs of legs,

11, 12, being shown herein. The said legs are made of angle bars, so placed that their 55 angles define the corners of the support, all of the said legs, of course, having casters and being suitably connected to each other in a manner and for the purpose well known. The front pair of legs 11, 12, are suitably 60 connected together at their top ends by a transversely extending angle bar 13, the horizontal flange of which is spaced below the top ends of said legs, and the bottom ends of said legs are connected by a smaller 65 angle bar 14.

The tub 10 is made of sheet metal and includes an upright front wall 15 which is spaced back of or within the vertical plane of the legs 11 and 12. A horizontal plate 16 (see Fig. 3) forms a top closure for the space 70 between said front wall 15 and the angle bar 13 at the top of said legs. The plate 16 is bent about the upright flange of the angle bar 13 and terminates in an upright, trans- 75 versely extending wall 17 arranged in the plane of the front faces of the legs 11 and 12. To the bottom edge of the wall 17 is hinged an apron or door 18 which provides a closure for the space between said legs 11 80 and 12 and the front wall 15 of the tub body 10. The said front wall 15 is extended upwardly and forwardly from the plate 16 into the plane of the top edge of the angle bar 13 where it is attached to a second horizontal 85 plate 19 which forms in effect a continuation of a lid 20 for the tub body. This lid is of familiar construction and is capable of being raised into an open position to give access to the interior of the tub body. 90

25 indicates a bracket plate upon which is mounted and carried the power transmission or gearing mechanism. Said plate is located within and toward the bottom of the space provided between the front end wall 15 of 95 the tub body and the front legs 11 and 12, and is rigidly fixed to said front legs. It comprises a body of suitable form which is placed adjacent the upright front wall 15 of the tub, and a plurality of laterally extending arms 26, 27, which are fixed respectively to the said front legs 11 and 12. Between its ends and at its top, the said bracket plate has an overhanging, forwardly extending arm which terminates in a depending flange 100 105 28. Said flange and the body of said bracket

plate provide a bearing for a horizontally disposed shaft 29 which is capable of being driven or rotated first in one direction and then in the other direction. This shaft 29 extends through the front wall 15 of the tub body 10 into the interior thereof, where it is adapted for operative, detachable engagement with an operating device 30 which, in this case, is the clothes receiving cylinder, indicated in dotted lines in Fig. 1.

31 indicates a horizontally disposed shaft which is the power shaft of the operating gearing. Said shaft is adapted for continuous, rotary motion in one direction and is journaled at its ends in the body of the plate 25 and the bottom end of the depending flange 28, respectively, in a plane below and parallel with the shaft 29. A pulley 32 of quite large diameter is fixed to that end of said shaft 31 which projects beyond the front face of the flange 28, and said pulley is driven by a belt 33 from the armature shaft 34 of a motor suitably mounted on the tub body, behind an upright plate 35 fixed to the angle bar 14. This plate is bent inwardly at its top end to meet the front end wall 15 of the tub body.

Fixed to the shaft 31 near the body of the plate 25 is a spur pinion 36 which meshes with a spur gear 37 of larger diameter, rotatively mounted on a stud 38 fixed in the body of said bracket plate, in a plane to one side of and somewhat below the shaft 31. A spur gear 39 of smaller diameter is made integral with the gear 37, and said gear 39 meshes with a larger spur gear 40 rotatively mounted on a stud 41 fixed in the bracket plate 25 in a plane to one side of and above the stud 38 and nearer to the leg 11. The large gear 40 has a crank pin 42 which is operatively connected to a rack bar 43 and said rack bar is adapted to impart a rotary, oscillatory movement to a segmental gear 44 loosely mounted in the shaft 29 adjacent the inner face of the depending flange 28. A roller 45 mounted loosely on the shaft 31 supports the free end of the rack bar 43 in operative engagement with the segmental gear 44. A suitable clutch device 46 is provided on the shaft 29 by means of which said shaft may be operatively connected to and disconnected from the segmental gear 44, said clutch device being controlled by a lever 47 outside the tub body near the leg 11. This lever is fixed on the outer end of a rock shaft 48 which terminates at its inner end near said clutch device.

It is apparent from the foregoing description that the continuous, rotary movement of the shaft 31 is imparted at a slower speed by means of the gears 37, 39, and 40 and the rack bar 43 before mentioned, into a rotary, oscillatory movement of the segmental gear 44, which movement is trans-

mitted to the shaft 29 and associated operating device 30, through the clutch device 46 at the will of the operator.

50 indicates a horizontally disposed, transversely extending shaft, which is located in a plane above and which extends at a right angle to the shaft 29. This shaft 50 is journaled at its inner end, in the top end of the depending flange 28, and at its outer end in a suitable bearing sleeve 50^a made integral with that part of the bracket plate 25 fixed to the upright leg 11. Loosely mounted on the shaft 50, nearer its outer than its inner end, are oppositely facing bevel gears 51, 52, which are provided on their opposed faces with clutches 51^a, 52^a, respectively. Said bevel gears mesh with a larger bevel gear 53 fixed to and co-axial with a spur gear 54 mounted in a suitable stud (not shown) projecting forwardly from the bracket plate 25. The spur gear 54 meshes with and is driven by the spur gear 40 before mentioned. A clutch collar 55 is keyed on the shaft 50 between the gears 51, 52, and is adapted to engage either of the clutches 51^a, 52^a, of said gears, so that the shaft 50 may be driven in either direction or remain idle, even when the gear 54 is rotating.

A bell crank lever 56 mounted on a stud 57 on the bracket 25, has a depending arm 58 which engages with said clutch collar, while its laterally extending arm 59 projects through an opening 60 (see Fig. 2) in the side wall of the tub body near the front leg 11. The projecting end of the lateral arm 59 engages in an opening 61 in an arm of a two-part controlling lever 62 which is pivoted on a lug 63 made integral with a casing 64 fixed to the before mentioned side wall of the tub body and the leg 11, respectively, by means of screws 65. Said controlling lever co-acts with arcuately spaced notches 66, 67, and 68 respectively, formed in the top curved wall 64^a of the casing 64. The said notches correspond with the two engaging and the neutral positions of the clutch collar 55 relative to the gears 51, 52.

70 indicates a short upright shaft, which is journaled in a bearing sleeve 71 forming a part of the bracket 25, and located in the angle of the leg 11 in a plane above that of the shaft 50. This upright shaft has a bevel gear 72 fixed to its bottom end which meshes with a similar gear 73 fixed to the shaft 50 adjacent the bevel gear 51 thereon. To the top end of the shaft 70 which terminates in a plane below the angle bar 13 before mentioned, is a collar 75, said collar and the gear 72 preventing endwise movement of the shaft 70 in its bearing sleeve.

76 indicates a second upright shaft arranged in axial alinement with the shaft 70 just mentioned, and said second upright shaft is journaled in a bearing block 77 fixed

to the leg 11 and angle bar 13, respectively, at their junction. This shaft 76 has fixed to its bottom end, a collar 79 which is coupled to the sleeve 75 in a manner to provide a flexible driving connection between the shafts 70, 76, which will compensate for such disalignment as may occur in assembling of the parts. The shafts 70, 76, thus form in effect, a single, flexible 10 shaft.

The bearing block 77 projects for some distance beyond the top of the horizontal plate 19 forming a part of the tub body 10 where it is reduced in diameter to provide 15 a sleeve 78 and upon which is rotatively mounted a bracket 80. Said bracket is adapted to be attached to and support a wringer 81 in such manner that the wringer may be swung horizontally about the shaft 20 76 as an axis, in any desired position, there being means for locking the bracket and wringer in said desired position. The bracket 80 comprises a tubular sleeve 82 which is adapted to be mounted on the 25 sleeve 78 before mentioned, and a laterally extending arm 83 which is adapted for attachment to the frame of the wringer 81. The top part of the sleeve 82 terminates in a shell 84, which, together with a removable 30 cap piece 85, forms a gear casing, as will soon be apparent. The laterally extending arm 83 includes a bearing sleeve 86 in which is journaled the projecting end of the lower wringer roll shaft 81^a, a bevel gear 35 87 being fixed to that end of said shaft within the gear casing formed by the shell 84 and the cap 85 before mentioned. The gear 87 meshes with a similar gear 88 fixed to the top end of the upright shaft 76 before 40 mentioned. A hand wheel 90 is screw-threaded through the sleeve 82 of the bracket 80 and by means of which the said bracket and associated wringer are held in the desired, adjusted horizontal position.

45 It is apparent that by means of the two-part controlling lever 62 before described, the clutch 55 on the shaft 50 may be brought into operative engagement with either of the gears 51, 52, so that said shaft 50 may be rotatively driven in either direction. This rotation of the shaft 50, through the gears 72 and 73 is imparted to the upright shafts 70 and 76 and consequently through the gears 88 and 87 to the wringer shaft 81^a.

50 My improved gearing possesses many advantages. All of the operating parts of the gearing are inclosed, thus insuring safety to the operator, and a noiseless mechanism. By the construction of and connection between the upright shafts 70 and 76 before mentioned, any slight inaccuracies as may exist, may be accommodated for in assembling the parts. By loosening the hand wheel, the wringer may be swung into any desired 55 horizontal position without disengagement

between the gears 88 and 87 after which said wringer may be locked in the new adjusted position.

While in describing my invention, I have referred to certain details of mechanical construction and arrangement of parts, I do not wish to be limited thereto except as may be pointed out in the appended claims.

I claim as my invention:

1. In combination, a main support having 75 an upright end wall, legs for said support, said end wall being spaced inwardly from the legs at that end of the support to provide a gear casing integral with the support structure of which the end wall is a part, a 80 gearing including a horizontally disposed, reversible shaft in said casing, an upright shaft in said gear casing operatively engaged with said horizontally disposed, reversible shaft, an operating device carried 85 by said support and operatively connected to said upright shaft, said operating device being capable of a swinging movement in a horizontal plane about said upright shaft as an axis, and means without said support 90 for controlling the operative movement of said horizontally disposed, reversible shaft.

2. In combination, a main support having an upright end wall, legs for said support, said end wall being spaced inwardly from 95 the legs at that end of the support to provide a gear casing, a gearing including a horizontally disposed, reversible shaft in said casing, an upright shaft in said gear casing operatively engaged with said horizontally disposed, reversible shaft, said upright shaft including a flexible coupling, an operating device carried by said support and operatively connected to said upright shaft, said operating device being capable of a 100 swinging movement in a horizontal plane about said upright shaft as an axis, and means without said support for controlling the operative movement of said horizontally disposed, reversible shaft. 110

3. In combination, a main support having an upright end wall, legs for said support arranged in pairs, one pair of legs being connected near their top ends by a brace bar, said end wall being spaced inwardly from said brace bar to provide a gear casing, a gearing within said gear casing, including a horizontally disposed, reversible shaft, bearing sleeves located in the angle of one of said legs, one of said 115 bearing sleeves also being fixed to said brace bar, an upright shaft journaled in said bearing sleeves and operatively connected to said horizontally disposed, reversible shaft, an operating device located in 120 a plane above the top of said main support, a bracket fixed to said operating device and including a sleeve adapted to be rotatively mounted on the bearing sleeve 125 fixed to said brace bar, said operating device 130

vice being capable of a swinging movement in a horizontal plane about said upright shaft as an axis, without disengagement therefrom, and means without said support for controlling the operative movement of said horizontally disposed, reversible shaft. In testimony that I claim the foregoing

as my invention I affix my signature in the presence of two witnesses, this 30th day of April A. D. 1917.
